PATENTED NOV. 20, 1906.

V. C. J. NIGHTINGALL.

CONTROLLER FOR USE IN CONNECTION WITH THE IGNITION OF GAS BURNERS.

APPLICATION FILED OCT. 30, 1905.

UNITED STATES PATENT OFFICE.

VICTOR CHARLES JOHN NIGHTINGALL, OF MELBOURNE, VICTORIA,
AUSTRALIA.

CONTROLLER FOR USE IN CONNECTION WITH THE IGNITION OF GAS-BURNERS.

No. 836,274.

Specification of Letters Patent.

Patented Nov. 20, 1906.

Application filed October 30, 1905. Serial No. 285,032.

To all whom it may concern:

Be it known that I, VICTOR CHARLES JOHN NIGHTINGALL, a subject of the King of Great Britain and Ireland, residing at 265^a Post Office Place, in the city of Melbourne, county of Bourke, State of Victoria, and Commonwealth of Australia, have invented certain new and useful Improvements in Controllers for Use in Connection with the Ignition of Gas-Burners, of which the following is a specification.

The object of my invention is to provide means to cheaply and effectively control the ignition and extinction of a gas burner or burners of any description that are ignited by means of a pilot-flame, platinum, or like means.

My invention, which accomplishes its end by the means hereinafter described, is particularly adapted for igniting or extinguishing burners surrounded by incandescent mantles or hoods and may be operated from any point over any distance and so situated as to control any number of burners, either individually or simultaneously.

My invention can be fitted to existing gas-light fittings at but slight additional expense and is operated from any source of electric energy, which may consist of a battery in use for other purposes. If necessary, however, a special battery may be employed.

My invention is applicable, moreover, not only for controlling the illumination of household or other buildings, but also for street or train lighting and other purposes.

In the past various devices have been employed to automatically ignite gas-burners either individually or simultaneously, but they have been inefficient in operation and in addition have been costly of installation and maintenance. With my invention these difficulties are overcome, and no skill is required to operate it; but in order that my invention may be better understood I will now refer to the accompanying sheet of drawings, which are to be taken as part of this specification and read herewith.

Figure 1 represents in section my invention complete as applied to an ordinary incandescent gas-burner. The valve is resting upon its seating and the supply of gas thereby cut off. In this figure my platinum attachment is in place and can be clearly seen. Fig. 2 is a side elevation of the various parts

of a controller. For the convenience of illustration the insulated wire and outer casing are removed. A pilot-tube with branches leading to three burners is specially illustrated. Fig. 3 is a side elevation, partly in section, of a modification in which the permanent magnet is dispensed with. The armature and valve are in the position they occupy when the supply of gas is free to flow to the burner. Fig. 4 is a view, partly in section, on a reduced scale illustrating my invention as applied to street-lighting and showing the electric conductors or wires passing through a gas-service main and also the connections to a lamp.

Similar letters of reference indicate similar or corresponding parts where they occur in the several views.

My invention includes a cylindrical casing or tube, which is made of any suitable magnetic metal, but preferably of soft iron. Its length and diameter depend upon circumstances and the conditions surrounding its use. It is hereinafter referred to as the controller-magnet A. This controller-magnet A is open at its top A' and has an extension B, which at its bottom is closed. Through the bottom of the said extension B, I form a perforation or hole B' to accommodate and act as a guide for a valve-spindle C', hereinafter mentioned. Between the said controller-magnet A and the extension B thereof is a flange B². In the said extension B is a radial elongated hole or gas-inlet passage D'. This communicates with the main gas passage-way D existing within the interior of the controller-magnet A. The top A' of the controller-magnet has portion of its interior removed and is provided with a thread, into which is screwed a valve-chamber E, hereinafter mentioned, or the said valve-chamber may be introduced into the top of the controller-magnet in any other suitable way, or it may be integral therewith. The valve-chamber E referred to consists of a metallic tube, and if it is a separate one preferably has a male thread around its exterior, which thread engages with a female thread within the interior of the controller-magnet. Within the valve-chamber is a valve-seating E' and a gas-inlet D². Through the hole B' in the bottom extension B of the controller-magnet and passing upwardly through the same and extending past the valve-seating

E' in the valve-chamber is a vertical spindle, which is hereinafter called the "valve-spindle" C'. At its lower end the said valve-spindle is secured to a disk or other shaped piece of soft iron. This is hereinafter called the "armature" C. The controller-magnet, the armature, and the valve-spindle may, if necessary, be nickelized or otherwise suitably prepared. At the top end of the spindle is attached the valve C². This valve is cone-shaped and has a flange around its periphery which when it rests upon the seating E' within the valve-chamber effectually prevents the gas passing upward to the burner. The said spindle C' is of such a length that when the valve C² is resting upon its seating the air-gap A² existing between the controller-magnet and the armature is less than the air-space F' existing between the armature C and the permanent magnet F at the bottom of the gas-chamber G, both hereinafter mentioned.

The Bunsen or other burner may be connected to the valve-chamber E in any well-known way; but in some cases—such as for street-lighting, &c.—the controller is not situated in close proximity to the burner, but may be placed where most convenient to operate a number of burners simultaneously.

- o At the top of the controller-magnet A is a ring or collar A³ of suitable non-conducting material. This ring or collar A³ may be formed integral with the controller-magnet; but if it is separate it is preferably threaded upon the valve-chamber E and rests upon the top A' of the said controller-magnet. Around the controller-magnet and between the ring or collar A³ and the flange B² is wound a length or coil of insulated wire H of any suitable gage. The two ends of this insulated wire H are led away or connected to wires leading to the point of control, which is connected to any suitable source of electric energy or battery. The extension B of the lower end of the controller-magnet has around its exterior a male thread. This engages with a female thread within a gas-chamber G. This gas-chamber is of suitable metallic construction and is preferably in the form of a cup and of sufficient depth to accommodate the armature C and allow it to move freely up and down therein. The gas-chamber G has an integral threaded extension or connecting-piece G', or the said connecting-piece may be separate and attached to the gas-chamber in any other suitable way. It may be at the bottom of the gas-chamber, as shown, or at the side of the same. The said connecting-piece G' has a gas-inlet G², which communicates at one end with the inlet-hole G³ in the gas-chamber and at its other with the supply-pipe. Protruding from the gas-chamber is a small tubular extension J. (See Fig. 3.) This has a longitudinal hole J' therein. This hole J' com-

municates with the gas-chamber G and with a hole J² in the top of the said extension and into which is inserted and secured therein in any well-known way the pilot-tube J³.

An electro or permanent magnet, which is hereinafter called the "permanent" magnet F, is preferably loosely mounted upon the connecting-piece G'. This permanent magnet F may be of any suitable shape or size and may be either vertical or horizontal, or both; but one end of it must be directly under the gas-chamber G. Preferably the magnet is made as shown in the drawings. The magnet may be retained in position in any well-known way; but preferably I provide a union K, which not only serves to retain the said permanent magnet F in position, but also to connect my invention and the burner to the gas-supply pipe or fitting.

To protect the controller and insulating-wire, I may provide an outer casing L of any suitable material. This fits loosely around the flange B² and collar A³ on the controller-magnet A and is removable. The pilot-tube J³ is preferably made as shown in Fig. 3 of the drawings; but it may be placed in any other convenient position.

When my platinum igniter, as seen in Fig. 1 and hereinafter described, is employed, I protect the chimney from damage by attaching a shield J⁴ to the burner-fittings. In some cases a pilot-flame may be used to ignite the burner; but, if necessary, I may employ a platinum igniter of special construction.

When the platinum igniter is used, the supply of gas through the pilot-tube is blocked by means of a plug or regulating-screw, as at J⁴ in Fig. 1. Should the platinum igniter become deranged, the plug may be regulated to permit the gas reaching the tube J³, which will then be used as an ordinary pilot-light.

This platinum igniter, as seen in Fig. 1, consists of a small piece of platinum wire M, arranged, preferably, as shown. Insulated wire M' is spirally wound around the pilot-tube J³ and connected to the platinum wire, or the said insulated wire may be conveyed to the platinum in any other suitable way. When the current of electricity is operated from the point of control hereinafter mentioned and the supply of gas is free to pass to the burner, a small quantity of the said gas is caused to pass over the said platinum wire M. This raises the temperature of the platinum by combining with the oxygen condensed on the surface of the platinum. Owing to its position in the gas, the platinum by itself is not of sufficient temperature to ignite the gas, but portion of the electric current mentioned passes through the insulated wire M', and when it reaches the platinum wire M it further increases the temperature thereof, when the gas is instantly ignited. To facilitate the ignition of the burner, I pro-

vide a creeping pilot, as at M² in Fig. 1. To prevent the platinum wire from burning out by an excess of current, I attach a small piece of resistance-wire m³ in the circuit of the platinum igniter.

When my invention is to be used in connection with street-lighting or similar extensive purposes, the wires conveying the electric current and leading from the point of control are entered into the service-mains and made secure and air-tight therein in any suitable or well-known way. The said wires are preferably insulated and are passed through the said mains and may be loose therein. The wires in the mains mentioned are connected to and are in circuit with the wires leading to the various lamps to be ignited. The said wires leading to each lamp are entered through the mains and made air-tight therein.

My invention is operated from a battery or other source of electric energy and is controlled by a switch and current-reverser of suitable construction. This switch and current-reverser I refer to as "the point of control." The said switch and current-reverser are so made that the flow of the electric current is cut off automatically after it has effected the purpose for which it is intended—that is, either to supply or cut off the gas. It will thus be seen that to operate it there is but a minimum flow of electric energy, and consequently no waste of any description.

In a modification I may dispense with the use of the permanent magnet F, in which case the electric current when switched on is maintained in a constant flow through the coil of insulated wire. This causes the controller-magnet A to remain magnetized while the current is maintained, so that it not only attracts the armature C to it, but also retains it in position, as seen in Fig. 3, where the valve is open and the gas free to flow to the burner or burners. When the current is switched off, the controller-magnet loses its attraction for the armature C, which latter in consequence falls by its own weight, and as it descends by means hereinbefore described automatically closes the valve.

In the modification the current-reverser is also dispensed with and an ordinary switch employed in its place.

The cycle of operations with my invention is as follows: When it is desired to ignite a burner or burners, the switch is operated from the point of control in a certain direction. The electric current from the source of energy flows freely around and through the controller-magnet, which attracts the armature C upward to it. The relative action of the permanent and controller magnets when the current-reverser has been operated in the said direction is such that the armature C is retained against the controller-magnet A.

The said armature C, when it is attracted up-

ward, carries the valve-spindle C' with it. This in turn lifts the valve C² from its seating E', and the gas passes freely from the passage-way D into the valve-chamber E and from there to the burner or burners, which are then ignited either by means of a pilot-flame or my platinum attachment, or other means.

When it is desired to shut off the supply of gas, the current is, from the point of control, reversed, and as it flows through the insulated wire and around the controller-magnet in a reverse direction causes the armature C to be attracted toward the permanent magnet F. As the armature descends it carries the spindle C' with it, and the valve C² thereon fits into its seating E' in the valve-chamber E, and the supply of gas is thereby shut off.

In the modification the cycle of operations is similar, except that, as mentioned, the permanent magnet F and the current-reverser are both dispensed with, and when a flow of gas is desired a continuous current is maintained through the controller-magnet A and causes the latter to attract the armature C and retain it in such position. When the supply of gas is to be cut off, the switch is operated and the current shut off. This causes armature C to be repelled from the controller-magnet A when it once falls, and by the means described the supply of gas is cut off.

Having now fully described and ascertained my said invention and the manner in which it is to be performed, I declare that what I claim is—

1. In improvements in and relating to controllers for use in connection with the ignition of gas-burners, a controller-magnet consisting of a metallic tube having within it a gas passage-way and having around its circumference a length or coil of insulated wire, an extension at the bottom of said tube, formed with an inlet gas passage-way in said extension, and a hole at the bottom of said extension, a valve-chamber situated at the top of said controller-magnet, said valve-chamber being connected to the burner or to a pipe leading to a burner or burners, a valve seating in said chamber, an armature consisting of a metal disk, a valve-spindle connected at its lower end to said armature, a valve connected to the upper end of said valve-spindle, said valve being situated in said valve-chamber, said valve-spindle being capable of a vertical movement within the interior of the permanent magnet, valve-chamber, and gas-chamber, a gas-chamber at the bottom of the said controller-magnet and inclosing said armature, a flange on the extension of the controller-magnet and a ring or collar near the top of the same, said flange, ring or collar inclosing the aforesaid length or coil of insulated wire, an outer casing or protector, a pilot-tube communicating with a hole in an extension of the gas-chamber, said extension

having a gas passage-way, a connecting-piece protruding from the gas-chamber for attaching the burner to the fittings, all as and for the purposes hereinbefore described and 5 as illustrated in the drawings.

2. In improvements in and relating to controllers for use in connection with the ignition of gas-burners, a controller-magnet consisting of a metal tube having within it a gas 10 passage-way and having around its circumference a length or coil or insulated wire, an extension at the bottom of said tube, an inlet gas passage-way in said extension, formed with a hole in the bottom of said extension, a 15 valve-chamber situated at the top of said controller-magnet, said valve-chamber being connected to the burner or to the pipe leading to a burner or burners, a valve seating in said chamber, an armature consisting of a 20 metal disk, a valve-spindle connected at its lower end to said armature, a valve connected to the upper end of said valve-spindle, said valve being situated in said valve-chamber, said valve-spindle being capable of a vertical 25 movement within the interior of the permanent magnet, valve-chamber and gas-chamber, a gas-chamber at the bottom of the said controller-magnet and inclosing said armature, a flange on the extension of the controller-magnet and a ring or collar near the top 30 of the same, said flange, ring or collar inclosing the aforesaid length or coil of insulated wire, an outer casing or protector, a pilot-tube communicating with a hole in an extension of the gas-chamber, said extension having a gas passage-way, a connecting-piece protruding from the gas-chamber for attaching the burner to the fittings, in combination with a switch for permitting a continuous 35 flow of electric current in one direction from a suitable source through the aforesaid coil of insulated wire to magnetize the controller-magnet and cause it to attract and retain the armature to it until the said switch is operated in the reverse direction which causes the current to be cut off, all as and for the purposes hereinbefore described and as 40 illustrated in the drawings.
3. In improvements in and relating to controllers for use in connection with the ignition of gas-burners, a controller-magnet consisting of a metal tube having within it a gas 45 passage-way and having around its circumference a length or coil of insulated wire, an extension at the bottom of said tube, an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower 50 end to said armature, a valve connected to the upper end of said valve-spindle, said valve being situated in said valve-chamber, said valve-spindle being capable of a vertical movement within the interior of the permanent magnet, valve-chamber and gas-chamber, 55 an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower 60 end to said armature, a valve connected to the upper end of said valve-spindle, said valve being situated in said valve-chamber, said valve-spindle being capable of a vertical movement within the interior of the permanent magnet, valve-chamber and gas-chamber, 65 an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal

disk, a valve-spindle connected at its lower end to said armature, a valve connected to the upper end of said valve-spindle, said valve being situated in said valve-chamber, said valve-spindle being capable of a vertical 70 movement within the interior of the permanent magnet, valve-chamber and gas-chamber, a gas-chamber at the bottom of the said controller-magnet and inclosing said armature, a flange on the extension of the controller-magnet and a ring or collar near the top 75 of the same, said flange, ring or collar inclosing the aforesaid length or coil of insulated wire, an outer casing or protector, a pilot-tube communicating with a hole in an extension of the gas-chamber, said extension having a gas passage-way, a connecting-piece protruding from the gas-chamber for attaching the burner to the fittings, in combination with a switch for permitting a continuous 80 flow of electric current in one direction from a suitable source through the aforesaid coil of insulated wire to magnetize the controller-magnet and cause it to attract and retain the armature to it until the said switch is operated in the reverse direction which causes the current to be cut off, all as and for the purposes hereinbefore described and as 85 illustrated in the drawings.

4. In improvements in and relating to controllers for use in connection with the ignition of gas-burners, a platinum igniter consisting of a platinum wire mounted upon or near the top of a metallic tube and connected to an insulated wire supported by a metallic 90 tube, said platinum wire being in close proximity to a creeping-pilot on the burner, said insulated wire having a resistance-wire within its circuit, said insulated wire also being connected to a coil of insulated wire deriving 95 its energy from any suitable source, and a pilot-tube in communication with an extension of a gas-chamber, said extension having a plug or regulating-screw therein.

5. In improvements in and relating to controllers for use in connection with the ignition of gas-burners, a controller-magnet consisting of a metallic tube having within it a gas passage-way and having around its circumference a length or coil of insulated wire, an extension at the bottom of said tube, an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower end to said armature, a valve connected to the upper end of said valve-spindle, said valve being situated in said valve-chamber, said valve-spindle being capable of a vertical 100 movement within the interior of the permanent magnet, valve-chamber and gas-chamber, an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower 105 end to said armature, a valve connected to the upper end of said valve-spindle, said valve being situated in said valve-chamber, said valve-spindle being capable of a vertical movement within the interior of the permanent magnet, valve-chamber and gas-chamber, 110 an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower 115 end to said armature, a valve connected to the upper end of said valve-spindle, said valve being situated in said valve-chamber, said valve-spindle being capable of a vertical movement within the interior of the permanent magnet, valve-chamber and gas-chamber, 120 an inlet gas passage-way in said extension, a hole in the bottom of said extension, a valve-chamber situated at the top of said controller-magnet, said valve-chamber being connected to the burner or to the pipe leading to a burner or burners, a valve seating in said chamber, an armature consisting of a metal disk, a valve-spindle connected at its lower 125 end to said armature, a valve connected to the upper end of said valve-spindle, said valve being situated in said valve-chamber, said valve-spindle being capable of a vertical movement within the interior of the permanent magnet, valve-chamber and gas-chamber, 130

ber, a gas-chamber at the bottom of the said controller-magnet and inclosing said armature, a flange on the extension of the controller-magnet and a ring or collar near the top 5 of the same, said flange, ring or collar inclosing the aforesaid length or coil of insulated wire, an outer casing or protector, a pilot-tube communicating with a hole in an extension of the gas-chamber, said extension hav-

ing a gas passage-way, and a connecting-¹⁰ piece protruding from the gas-chamber for attaching the burner to the fittings.

In testimony whereof I affix my signature in the presence of two subscribing witnesses.

VICTOR CHARLES JOHN NIGHTINGALL.
